AUTOMATIC WINDING MACHINE

Winthrop L. Perry, Milford, N.H., assignor to Abbott Machine Co., Inc., Wilton, N.H., a corporation of New Hampshire
Original application Sept. 29, 1961, Ser. No. 141,884, now Patent No. 3,168,257, dated Feb. 2, 1965. Divided and this application May 28, 1964, Ser. No. 371,068

7 Claims. (Cl. 242—35.5)

This application is a division of my application Serial No. 141,884, filed September 29, 1961, now Patent No. 3,168,257, for Winding Machine.

One of the objects of the invention is to provide detector-controlled driving mechanism for tending mechanism which can very quickly and reliably institute a cycle of operation of a cam carrier that operates the tending mechanism.

The said application Serial No. 141,884 describes and illustrates all of the several components of two systems of tending mechanism, one of which systems is put into operation whenever a stopped or non-winding unit is presented to detecting mechanism, and other of which systems is put into operation only in case such stopped or non-winding unit lacks a supply end of yarn suitable for tying to the yarn of the package of the unit. The said application Serial No. 141,884 may be referred to for its disclosure of all these components of the two systems. For simplicity, the present application will not again describe in detail all the components of the first system but as to this first system will deal mainly with one of its major components which comes into play early in the cycle of tending, namely the bobbin end carrier mechanism. When the second system operates in case of lack of available yarn, bobbin changing mechanism of this second system also comes into play early in the cycle.

The present application further involves an improvement in bobbin-end carrier mechanism adapting this to operate while a unit which requires tending is taking a step of motion from a position where detection has been made to another position where the package yarn end-finding operation will be performed. This end carrier mechanism is especially adapted not to interfere with the yarn of any properly winding unit traveling past it.

In the accompanying drawings:

FIG. 1 is a schematic perspective view intended primarily to locate the tending mechanism of the machine with reference to a plurality of winding units which are moved past the tending mechanism.

FIG. 2 is a diagram in the nature of an elevation showing certain parts of a winding unit of the machine in winding operation.

FIG. 3 is a detailed view showing the interconnection between two of the parts shown in FIG. 2.

FIG. 4 is a view similar to FIG. 2 but showing the winding unit in an inactive non-winding condition.

FIG. 5 is a detailed view mainly in vertical section showing the mounting of an indicating and controlling pin of a winding unit.

FIG. 6 is a general view explanatory of the construction and operation of clutches in the machine.

FIG. 7 shows one of the clutches, this view being taken at right angles to FIG. 6, and also shows this clutch serving to connect a vertical drive shaft with a horizontal cam shaft in the tending mechanism.

FIG. 8 is a diagrammatic view in the nature of a plan with numerous parts removed, showing feeler and clutch control mechanism.

FIG. 9 is a fragmentary view showing a different position of the feeler mechanism of FIG. 8.

2

FIG. 10 is a fragmentary view showing a still different position of portions of the feeler mechanism of FIG. 8.

FIG. 11 and FIG. 12 are diagrammatic views in the nature of elevations showing respectively upper and lower portions of feeler and clutch control mechanism of the machine.

FIG. 13 is a diagrammatic view in the nature of an elevation showing tending mechanism.

10 FIG. 14 is a fragmentary view showing a position of the package yarn end-finding nozzle in engaging a very small diameter package.

FIG. 15 is a diagram showing bobbin end carrier mechanism and associated parts.

15 FIG. 16 is a detail view of the body portion of the bobbin end carrier.

FIG. 17 is a fragmentary view showing a portion of the end carrier in different positions.

20 FIG. 18 is a fragmentary plan view showing certain parts of the bobbin magazine and operating connections for certain parts associated therewith.

FIG. 19 is a diagram in the nature of an elevation, principally showing bobbin-chute mechanism.

25 FIG. 20 is a detail view taken on the view line 20 of FIG. 19 showing the lower portion of the bobbin chute.

FIG. 21 is a fragmentary view taken from the right of FIG. 19.

30 FIG. 22 is a diagram in the nature of a plan showing parts of the bobbin magazine and certain parts associated therewith.

FIG. 23 is a perspective showing bobbin doffing mechanism.

FIG. 24 is a diagram in the nature of a plan showing cam-operated rods and valves.

35 FIG. 25A is a schematic representation, in perspective, showing the yarn running from the bobbin of a traveling winding unit as passing along the face of the yarn end carrier, when this is inactive, and also showing the inactive position of a pivoted yarn plow or hook.

40 FIG. 25B is a similar view showing the carrier in condition to detain a broken yarn.

FIG. 25C is a similar view showing the yarn detained and clamped.

45 FIG. 25D is a similar view showing the hook swinging down and showing the tail of the yarn as having been pulled out of the stub catcher.

The individual winding units, W, FIG. 1, the rotatable table carrying these and the mechanism for driving the package of each winding unit in a winding direction and the mechanism for driving the package in a reverse direction for end-finding are all shown and described in said application Serial No. 141,884.

50 The mechanism for stopping winding on any unit upon breakage or exhaustion of yarn is likewise disclosed in Serial No. 141,884, and in the present application FIGS. 2 and 4 which show parts of this mechanism are included principally in order to show two positions of a pin 227, held down in normal winding as in FIG. 2 (against the lifting tendency of a weight-loaded lever 227a, FIG. 5) and somewhat raised in FIG. 4, this latter position being the position assumed by the pin when the unit has been disconnected from its winding-direction driving means.

55 In FIG. 2 the yarn detector element 65 is up in its running position, where held by the yarn, and an associated lever 66 acts through a link 67 to hold a link 219a out of reach of an oscillating knock-off lever 200b, an arm 185 which pivots at 186 with the pivotally mounted drive receiving roll 180 now being in an upper position holding up a link 219, causing a lever 229 to bear on the head of the pin 227 and hold this down.

In FIG. 4, the winding unit has been stopped, its drive receiving wheel 180 in a neutral position, its lever 185 forced downwardly (clockwise about the pivot 186) and latched in this position by latch lever 224 engaging a projection 226 on lever 185, the link 219 in this position having swung lever 229 about a pivot 225 to lift it off the pin 227 and allow the pin 227 to rise.

The mechanism whereby the pin 227 is subsequently given further upward movement from its position of FIG. 4 and employed to unlatch the lever 185 and also to move the drive-receiving wheel 180 into drive-receiving relation to the reverse driving mechanism, and subsequently restore the winding unit into operating condition is described in more detail in a further divisional application for automatic winding machine on or about the same date as this application.

The element 231, pivoted at 232 to the latch lever 224 and having a pin 231a extending through a hole 224a in the latch lever is for the purpose of swinging the latch lever 224 in subsequent unlatching of lever 185, this element 231 being idle at the stage when the parts come into the positions of FIG. 4.

Since the machine's two systems of tending mechanism are controlled by clutches 240 and 242 respectively and the step-by-step travel of the units is controlled by clutch 241, and these clutches are of peculiar construction, it will be convenient to describe the construction and operation of these clutches before describing their controls.

Referring to FIG. 6 such a clutch, intended to rotate in the direction indicated, may have a pawl carrier element 245 having pivoted thereto alternate tail-less and long-tailed pawls 246, 247 and 248, 249, the long-tailed pawls having their tails in the trailing direction. The pawls are urged inwardly by spring wires 250 and 251 which interconnect pairs of pawls. The tailless pawls are to prevent overrunning.

A pin carrier element 255, in the simplest case, carries a single pin 256 adapted to be engaged by the forward face of either long-tailed pawl, to be driven thereby. A movable stop element, represented by 258, in the path of the long tail will trip a long-tailed pawl and withdraw it from the pin and declutch the drive. With a single pin 256 and with a single stop element normally in the path of the long tails, the clutch will function as a one revolution clutch. Removing the stop element long enough to allow a pawl to pick up the pin will drive the pin carrier through one revolution.

The clutches referred to as 240 and 242 operate in this manner.

With a second such pin 256a added, with the stop member 258 normally removed from the pawl patch, and with a second stop 258a permanently positioned to trip a pawl at approximately 180° from the position at which a pawl may be tripped by movable stop 258, such a clutch will normally drive continuously. Then if the movable stop member is operated to trip one long-tailed pawl while the other long-tailed pawl is in tripped position in passing the permanent stop 258a, the pin carrier will skip one-half revolution. The clutch referred to as 241 is operated in this manner.

The drive to the table 52 is from a motor M-2, FIG. 12, through pulley 261, friction drive wheel 262, pinion 263, gear 264, pinion 265, 266 and vertical shaft 270. Shaft 270, FIG. 11, is normally coupled by clutch 241, operated as described above, to a sleeve 271 which carries oppositely directed crank arm 272 carrying Geneva drive rolls 273. These rolls enter the Geneva grooves in the underside of the table 52, each roll 273 advancing the table 30° each time it engages one of the Geneva grooves.

At its bottom end the shaft 270 is connected through bevel gears 280 and 281, FIG. 7, to a sleeve 283 carrying the pawl carrier 245 of clutch 240, the pin carrier 255 of this clutch being fast on a horizontal cam shaft 285. This shaft 285 is operated through the clutch 240 each

time that a winding unit requires to be tended, regardless of whether a new bobbin requires to be supplied, this shaft 285 being the cam carrier of the first system of tending mechanism.

The vertical shaft 270 also carries the pawl carrier 245 of the clutch 242, FIG. 11, the pin carrier 255 of this clutch being carried by a sleeve 287 which is rotated through clutch 242 one revolution in those instances in which the bobbin is required to be changed. The sleeve 287 comprises the cam carrier of the second system of tending mechanism.

The sleeve 271 which is driven by clutch 241 carries a cam 290, FIGS. 11 and 8, against the surface of which a cam-followers roll 291 is yieldingly drawn. As the cam-follower roll moves toward the center of the cam, as permitted by the cam surface, a system of linkage operates. Motion of this linkage can be blocked, short of full movement, by two possibilities, first, by the pin 227 of the winding unit which is at the eleven o'clock position being in the depressed position, and second, by yarn being encountered by yarn feeding mechanism. In the first situation, the winding unit is allowed to continue running without the tending mechanism affecting it. In the second situation, where the winding unit is not running but yarn is present, so much of the tending mechanism as is appropriate to this situation will operate, particularly clutch 240, shaft 285 and mechanism driven thereby, i.e., the first system of tending mechanism.

In the further situation in which the linkage is not blocked but has its full motion, the additional portions of the tending mechanism concerned with changing the supply bobbin are operated, particularly the clutch 242, sleeve 287 and parts operated thereby, i.e., the second system of tending mechanism.

Operation of the tending mechanism, either with or without supply of a new bobbin is accompanied by operation of the clutch 241 to skip one-half a revolution of the sleeve 271 and Geneva drive, with the result that after the winding unit has been advanced to the twelve o'clock position where the tending operations largely take place the table is caused to dwell considerably longer than usual. The skipping of this half revolution also suspends operation of the cam 290 and certain control functions initiated by this cam.

The cam follower 291 is carried by a bell crank 292 having a lug 293, all of which are biased in a clockwise direction, FIG. 8, by a spring 294. At 292a the bell crank is pivotally connected to links 295 and 296. Link 295 serves as a connection to clutch 240. Link 296 serves as a connection to feeler mechanism. Link 296 is pivotally connected at 297 to an arm 298 which is fast on a shaft 299. Shaft 299 also carries a two armed crank 300 whose opposite ends are connected by links 301, 302 to crank arms 301a, 302a which are fast on shafts 301b, 302b. Arms 301c and 302c which are fast on these shafts carry stacks of vertically spaced feeler fingers 301d, 302d which are adapted to intermesh as indicated in FIG. 11.

When a winding unit reaches the eleven o'clock position its yarn, if present, extending from its bobbin up to its slab catcher, will lie in the region where these fingers tend to intermesh.

The rotation of cam 290 and the action of spring 294 will tend to allow the arms 301c and 302c to swing from behind the upright of the winding unit to the position of FIG. 8, and if the fingers encounter no yarn they will intermesh as shown. If the fingers do encounter yarn, the yarn blocks the fingers from intermeshing, this condition being shown in FIG. 9; and the cam follower 291 is prevented from fully following the drop in the contour of cam 290. This condition calls for retying the yarn of the winding unit.

The condition in which the fingers intermesh calls for change of the winding bobbin in addition to tying the end from the yarn package onto the new end of yarn.

However, most frequently the winding unit will be winding when it reaches the eleven o'clock position. Its pin 227 will be fully down. In this situation the lower end of the pin blocks a plate 298a which is fast to the arm 298, as shown in FIG. 10, and so blocks the linkage from moving the fingers 301d and 302d into detecting engagement with the yarn.

The three situations and corresponding conditions of the linkage have the following results. Link 295, as indicated, controls clutch 240. This control is through connections comprising a crank 310, FIG. 8, shaft 311 and crank 312, the end of which constitutes the previously described movable stop element (represented by 258 in the description of clutches) for the clutch 240.

When a winding unit is running at the eleven o'clock position the crank 312, acting as a stop, trips the clutch 240 thereby preventing drive of the horizontal cam shaft 285.

When a winding unit is not winding at the eleven o'clock position, the plate 298a not being blocked by pin 227, the crank 312 is out of range of the pawls of the clutch, allows engagement of the clutch and permits the horizontal cam shaft to be driven. This occurs whether the fingers 301d and 302d meet a yarn or fail to engage a yarn.

The feeler mechanism distinguishes between detection and non-detection of a yarn as follows.

A crank arm 315, FIGS. 8 and 11, which turns with the shaft 299 is adapted to engage a pin 316 on a crank arm 317 which turns with a shaft 318. Arm 317 is biased toward the clockwise direction by spring 319 acting on a crank arm 320 on shaft 318, but is moved counter-clockwise by the action of arm 315 on pin 316. A pin 321 on arm 317 constitutes the movable stop element represented by 258 in the description of clutches, for the clutch 242. This stop element is normally in position to trip the long-tailed pawl of clutch 242 and prevent operation of the clutch, but by movement of the linkage to the intermeshed condition of the fingers 301d and 302d of FIG. 8 the stop element is removed from the path of the pawls and clutch 242 is allowed to engage and drive the cam-carrying sleeve 287. This does not occur if the fingers are blocked from intermeshing by encountering a yarn as in FIG. 9.

Clutch 241 is omitted from the illustration of the mechanism in FIG. 8 because, lying at a level between cam 290 and clutch 242 its illustration would unduly obscure both. This clutch as mentioned normally connects a vertical shaft 270 to the sleeve 271 which drives the cam 290 and Geneva drive for the table.

Upon rotation of horizontal cam shaft 285 an eccentric 330 thereon operates through a link 331, a crank arm 332 shaft 333 and crank arm 334 (which later constitutes the movable stop element represented by 258 in the description of clutches) to move into the pawl path of clutch 241. In FIG. 8 the full line showing of arm 334 represents its normal position in which it does not trip the clutch 241 and the broken line showing represents the clutch-tripping position to which it is brought by the eccentric 330 after the cycle of rotation of horizontal cam shaft 285 has been initiated by detection of non-winding of a unit at the eleven o'clock position.

In the case of detection of a non-running winding unit a normally inactive bobbin-end carrier mechanism is operated by a cam 351, FIG. 24, on the horizontal cam shaft 285.

This carrier mechanism shown in FIGS. 15, 16 and 17 includes a yarn carrier slider 353 movable on a guide track 354 from a position adjacent to the path of yarn on the winding units traveling from eleven o'clock to twelve o'clock position, up to an elevated position of the slider 353. The slider 353 will engage a yarn which has broken and which has caught in the slab catcher S, FIG. 13, of the winding unit.

The slider is provided with a curved guiding surface 355 adapted to deflect a yarn toward the winding unit as the yarn approaches the region of a pin 360. Pin 360 is normally held retracted in a recess in the slider by a spring 361, so as not to disturb a yarn of a running winding unit, FIG. 25A. When linkage comprising lifter rod 351a, lever 351b and link 351c is operated by the cam 351 the slider 353 is raised and in the initial rise the pin 360 meets a roll 362 which projects the pin, as shown in broken lines in FIG. 17, causing it to catch the yarn extending down from the slab catcher, FIG. 25B. The pin then retracts in leaving the roll 362, gripping the yarn under the conical head of the pin, FIG. 25C and pulling the tail of yarn from the slab catcher, FIG. 25D.

15 As the slider 353 rises a pivoted yarn plow member 370, FIG. 15, is swung down to assist in withdrawing further yarn from the bobbin to provide a length appropriate for holding the yarn in position to be received by a knitter.

The yarn plow 370 is moved with the bobbin-end carrier 20 by linkage 370a, 370b, 370c, FIG. 15, from the lever 351b which operates the bobbin-end carrier.

A bobbin-end suction tube 380, FIG. 13, swings to meet the slider 353 at the top of the path of the slider and the suction is applied to the tube 380. Suction is created 25 in nozzle 380 by a jet 380a which is supplied with compressed air through a valve controlled by a cam on the horizontal cam shaft. A pervious bag 405a collects the yarn ends. As the tube 380 draws in yarn held by the slider 353 the pin 360 of the slider is again projected and 30 the yarn end is released to the suction tube. This second projection of pin 360 is caused by the pin striking a cam 365 adjacent to the top of the path of travel of the carrier. Discharge of the yarn from engagement with the pin 360 is insured by a lever 385 which lies in a slot in the body 35 of the slider and also in the head portion of the pin. The lever 385 is normally held retracted by a spring 385a sufficiently so as not to interfere with grasping and holding of the yarn by the pin. At the upper position where the yarn is to be released by the yarn end carrier a cam 40 366 engages a pin 385b to project the lever 385, as shown in FIG. 16, to push the yarn clear of the pin. The suction tube thereupon swings back to a retracted position in which the yarn end from the bobbin lies in position to be received by the knitter indicated generally by the 45 reference character 500. Suction nozzle 380 is carried by arm 380f, FIG. 22, which is pivoted at 308g and swings in conjunction with the motion of bobbin-end carrier 353 by a connecting link 380h which connects arm 380f with lever 351b, FIG. 13.

50 The bobbin-end carrier is allowed to operate with respect to any winding unit as to which non-winding is detected, even though no yarn is detected by the feeler mechanism. In this latter case, however, bobbin changing mechanism to be described will supply a new bobbin and 55 present its end to the knitter.

The package yarn end-finding nozzle mechanism indicated generally at 400 is as described in said application Serial No. 141,884 and in a divisional application Serial No. 210,996, filed July 19, 1962, now Patent No. 3,157,-60 368, for Automatic Winding Machine. FIG. 13 shows this mechanism in two positions, a broken line position wherein the lip 401 of the suction nozzle engages the yarn package P and a full line retracted position wherein the found yarn lies within the knitter 500.

65 The knitter is operated by the mechanism described in a further divisional application Serial No. 210,997, filed July 19, 1962, now Patent No. 3,152,821, for Knitter Operating Mechanisms.

The package end-finding mechanism and knitter, like 70 the bobbin end carrier mechanisms form components of the first tending systems and are operated in properly timed relation by cams on the cam shaft 285 each time the clutch 240 is operated.

The horizontal cam shaft 285, in addition to rotating the eccentric 330, the cam 238b for controlling the reverse

driving of the package and restarting of the package, the cam 351 for operating the yarn end carrier mechanism, the cam 585 for operating the upper and lower yarn pusher linkages, the cam 515a for operating the lifter rod 516 for the knotter, the cams 441 and 441a for raising and lowering the rod 444 which operates the package yarn end finding nozzle, and the cam 670 which operates switching means to cause the motor to run at slow speed, may also carry an index cam 680. The horizontal cam shaft also operates air valves 690 and 691 for admitting air blasts to jets connected respectively to the bobbin yarn suction nozzle and to the package yarn end-finding nozzle, and an air valve 692 for admitting compressed air to a nozzle directed at the tension device and slub catcher of a winding unit. Cams 690a, 691a and 692a on shaft 285 operate these valves.

All of these air valves are normally closed, and only opened in those cycles in which the horizontal cam shaft operates in tending a winding unit.

As previously indicated, if a winding unit is not running and if the yarn detector fingers do not encounter yarn but move to their intermeshed position, the clutch 242 is allowed to operate to drive the sleeve 287 one revolution. This operates the second tending system. Sleeve 287 carries cams which control the bobbin changing mechanism 600.

A bobbin magazine 601, FIG. 18, includes for example thirty-six open-sided bobbin pockets 602. These are attached to a ring 603 which is rotatable in grooved guide rolls on which the ring 603 rests, the ring being broken away in FIG. 18 to show such guide rolls. The bobbin pockets are open at their bottoms and the bobbins therein stand on guide rods 607 which, however, terminate at the position where a winding unit receives a new bobbin.

The ends of yarn of the bobbins are placed manually around a central conical end holder 609, FIG. 22, which is given a slow winding motion to keep the ends slightly tensioned and also to wind up the ends of yarn remaining after knot tying.

Advance of the magazine is by means of a cam 612, FIG. 19, on sleeve 287, the cam follower swinging a post 613 which operates through linkage 614 through 619, FIG. 18, to turn two swinging plates 621 and 622. These plates carry spring pressed pawls 623 shaped to engage with the curved rear faces of bobbin pockets, thus indexing the magazine to the extent of one pocket for each bobbin changing operation.

The cross-link 618 of the aforesaid linkage may also operate a ratchet to rotate the central conical holder.

A bobbin chute 630 is shown in four positions in FIG. 19.

The motion of the chute involves the pivotal attachment of the chute to a crank 636 at 636a and to a link 637 at 637a. These are operated respectively by connecting rods 638 and 639, rod 638 being operated by a rotatable post 640, and rod 639 by a rotatable sleeve 641, which in turn are operated by followers of cams 642 and 643 on sleeve 287. Normally the chute 630 is in its most retracted broken line position of FIG. 19, farthest removed from the course of the bobbins which are carried by the bobbin pegs 56 of the winding units and from the course of the yarns which are unwinding from those units which are actively running. When the chute operates it rises to the full line position of FIG. 19 and receives a bobbin which drops from a bobbin pocket 602 as the latter moves past the ends of wires 607. The chute with the new bobbin in it aligns itself with bobbin peg 56 as shown, the upper part of the peg being received within the chute. Inclined pieces 630a within the chute near its bottom prevent the bobbin from falling out endwise during this movement. The chute then retracts away from the bobbin pegs leaving the bobbin free to seat on the peg.

As a yarn which extends from a bobbin in a pocket to the central holder approaches the location of the knotter, the yarn is picked up by a stationary guide 644, FIG. 22,

on which the yarn then rides. When the magazine is indexed and the bobbin is released from its pocket and delivered by the chute, the yarn end of this bobbin is positioned by an oscillating finger 651 which is connected to link 652 and operated by the swinging plate 621. FIG. 22 shows in broken lines the position assumed by finger 651 when it delivers a yarn for knotting. The knotter rises, takes this new bobbin end and the package yarn end found as previously described by the suction nozzle, and ties them.

As in the case of tying an old bobbin end, the tied yarn is pushed into place and the winding unit restarted.

It should be mentioned that when a winding unit is to receive a new bobbin the old bobbin is first removed by a pivoted doffer tray 660, FIG. 23, whose outermost edge rises under the base of a bobbin on the bobbin peg, allowing the bobbin to topple away from the winding unit into the tray as the tray pivots around axis 660a. Further rise of the tray inclines the tray so that the bobbin slides endwise off the tray into a suitable receptacle, not shown. The doffer tray is operated from the follower of a cam 672 on the sleeve 287, through crank 675, sleeve 676, crank 677, link 678 and crank 679. The doffing operation is early in the cycle in order that the bobbin may be doffed without being moved along to the twelve o'clock position. It will be understood that no bobbin is doffed unless the cam-carrying sleeve 287 is operated through its clutch 242.

I claim:

1. In an automatic multiple-unit winding machine including tending mechanism adapted to operate upon the several winding units selectively to perform a tending operation in case required by the particular unit, a rotatable cam carrier for operating such tending mechanism, a clutch adapted to connect the cam carrier with a source of driving power, the clutch including a pawl element on its driving member and another element on its driven member engageable with said pawl element, means urging said pawl element toward engagement with said other element to establish driving relation between the driving and driven members of the clutch in one position of the pawl element relative to its member, and a stop element normally tripping the pawl at a place in its path of revolution to withhold the pawl from establishing such driving relation, a timing cam connected to said source of driving power, linkage for shifting said stop element to a position to allow said pawl element to establish such driving relation, and means for urging the linkage so to operate, the timing cam controlling the movement of the linkage by restraining the linkage against such operation of the linkage during part of the cam cycle, and permitting such operation of the linkage during another part of the cam cycle, detecting mechanism adapted to detect a condition of a winding unit not calling for operation of the tending mechanism, said detecting mechanism being adapted to block said linkage even when operation of the linkage is permitted by the timing cam.

2. An automatic winding machine as claimed in claim 1 in which the clutch includes two pawl elements on its driving member, the said element on the driven member being engageable with either said pawl element.

3. An automatic winding machine as claimed in claim 1 in which the detecting mechanism includes an element movable with the linkage under control of the timing cam.

4. Bobbin yarn end carrier mechanism for the tending mechanism of automatic winding machines having relative traveling movement between the tending mechanism and a plurality of winding units, which winding units include elements to which a broken yarn from the supply bobbin may extend, the machine including detecting mechanism for detecting a condition of a broken yarn calling for a tending operation upon a unit, the carrier mechanism including a carrier body member

movable from a first region of such broken yarn extending from the supply bobbin to a second region at a different level for handling of such yarn in the tending operation, the machine including means for so moving the carrier body member, a yarn-detaining member mounted in the carrier body member and adapted to be retracted therein to normally avoid catching a yarn of a winding unit, and means for projecting the yarn-detaining member to catch a broken yarn at the first region as relative movement occurs between the winding unit and the tending mechanism, and for again projecting the detaining member to release the broken yarn as the carrier body member is at the second region, and the carrier mechanism including means to retract the detaining member to grip the broken yarn during movement of the carrier body from the first region to the second region.

5. Bobbin yarn end carrier mechanism as claimed in claim 4 in which the carrier body member is provided with a yarn guiding surface adapted to deflect yarn toward the winding unit.

5 6. Bobbin yarn end carrier mechanism as claimed in claim 4 in which the detaining member is a pin having an enlarged head portion.

7. Bobbin yarn end carrier mechanism as claimed in claim 4 including means for pushing the yarn from the 10 detaining member upon release of the yarn.
